UNITED STATES PATENT OFFICE.

CHARLES F. DUTTON, JR., OF CLEVELAND, OHIO.

PROJECTION-LANTERN.

960,519.

Specification of Letters Patent. Patented June 7, 1910.

Application filed June 29, 1908. Serial No. 440,888.

To all whom it may concern:

Be it known that I, CHARLES F. DUTTON, Jr., a citizen of the United States, residing at Cleveland, in the county of Cuyahoga and State of Ohio, have invented certain new and useful Improvements in Projection-Lanterns, and do declare that the following is a full, clear, and exact description of the invention, which will enable others skilled in the art to which it appertains to make and use the same.

My invention relates to improvements in projection lanterns, and the improvement is comprised in an apparatus constructed and arranged to project an enlarged picture of an opaque object, such as a printed card, upon a screen; and further, to project a series of pictures in such a manner that a moving or motion effect is produced, all substantially as shown and described and particularly pointed out in the claim.

In the accompanying drawings, Figure 1 is a perspective view of the device complete. Fig. 2 is a detail view of one form of intermittent drive gear adapted to be used in my device. Fig. 3 is a plan view in section through the body of the lantern, and Fig. 4 is a front elevation thereof. Fig. 5 is a sectional view on a central vertical line of the rear portion of the device and showing more particularly the slide and mounting for the drive parts. Fig. 6 is a plan view of the lantern with the display disk in section to show its manner of attachment to the operating mechanism.

The body —2— of the lantern is angular in formation and especially in that the front wall —3— is inclined rearwardly at each side to bring the porcelain lamp sockets —4— and electric lamps 5 mounted thereon at the proper angle to direct the rays of light upon the card —6— or other object at the rear. The body is further provided with an integral or fixed tube —7— located between the lamps 5 and projecting rearwardly from the front wall to a point approximately opposite the middle of the lamps or in such relation thereto that the light from the lamps is more or less screened from the side at the inner mouth of the tube except as it is reflected in direct lines from the card or picture 6.

Fixed tube 7 supports a set of two or more extension tubes —8— and —9— sleeved one within the other, one of which carries a lens 10 for projecting and enlarging the picture.

The telescopic arrangement of the said tubes provides for the adjustment necessary in focusing the object on the screen, and because supporting tube —7— is largely within body —2—, the said extension tubes may also be retired within the body for compactness and convenience in packing and shipping.

The rear wall —11— is in reality a removable slide which is confined at its sides and bottom by a flange —12— on body 2 and is free to be lifted and removed from the top, and said slide has an opening —14— opposite the inner end of the lens tubes 70 and through which the picture or object is displayed. This picture or object may be either stationary or movable and may consist of a single card with a single picture thereon, or a tape or cord with a series of 75 pictures thereon. My apparatus is provided with a dual arrangement for displaying either single picture or sets of pictures, and in both instances the means for supporting and displaying the pictures, is mounted 80 upon slide wall 11 and becomes a removable part therewith. Thus, at the left of said wall 11, I pivotally attach a bail or set of links 15 which pivotally support a flat display board or plate —16— edgewise between their free ends, and upon which a picture card, such as picture postals or photos 6' may be removably placed by rubber bands 17 or clips or the like. Picture cards may be placed on both sides of the plate as 90 said plate is rotatably supported and either side may be swung opposite and in close relation to opening 14.

The foregoing arrangement provides for single pictures, but a series of pictures may 95 be also displayed in such rapid succession that a moving picture is the result, and to this latter end I provide a disk —18— having a series of pictures —19— concentrically arranged on one or both of its faces and 100 mount the same at the rear of the body upon suitable frame-work 20 which is part of or attached to slide wall 11. When the pictures on the disk —18— are to be displayed, the swinging frame embodying plate —16— and links —15— is moved to one side as seen in Fig. 1. Disk —18— is then slipped over the screw end of short shaft 21 which has bearing support midway of framework —20—, and the said disk brought face to face with 110 the hub of gear or notched wheel —22— and is locked against independent rotation there-

on by pins 23 which pass through correspondingly located openings in the disk, and thumbnut —24— then fastens the disk in place. The disk now occupies such relation 5 to the body and its lens tubes that the circuit of pictures on its face are brought into axial alinement with opening —14— and the lens when rotation is imparted to the disk. But a continuous rotation of the disk would only 10 present a blurred effect on the screen, and therefore, it is essential that an intermittent rotation be had which will present each picture in the series in turn and hold it without movement for a predetermined length of 15 time so that a distinct and clean cut reflection and reproduction thereof will appear. To that end, I provide a notched wheel 22 which is adapted to be engaged at its edge in the notches by a pin-wheel 25 once during 20 each revolution thereof, and which advances wheel 22 and the disk the requisite distance between pictures to display each in turn. During the interval when pin-wheel 25 is rotating to again operate wheel 22, a spring 25 detent or check member 26 holds said wheel 22 stationary. This member is adjustably supported upon frame-work 20 to increase or decrease its frictional contact. However, in Fig. 2, I disclose a modified form of gear- 30 ing in which the spring member is eliminated, the notched wheel 22 in this instance having an edge to edge relation to the single tooth pinion 27 and whereby its periphery is adapted to ride against and within the circular cut-out portions 28 of the gear or 35 wheel 22 to lock the latter against rotation when the single tooth of pinion 27 leaves the notch and during the interval before it rides into the next notch. For high speeds, 40 the latter construction is preferred, being more positive in its locking action.

Wheel 25 or pinion 27 may be crank driven direct, but for greater speed and smoother running a belt 29 is used to drive

the same from and by a larger wheel or 45 pulley 30 having a crank shaft and handle 31 mounted in a bearing at the end of extension 32 of framework 20 at the side of body 2 where it may be conveniently operated. 50

Rear slide wall 11 is made removable to give access to the interior of body 2 and so that electric lamps 5 may be removed and replaced and their electric connections —33— inspected and repairs made if needed. The 55 lamps used are of high power and preferably have a relatively larger diameter than length. I also prefer to use a lamp with a frosted front half —34— and a reflector back —35—. Having two lamps disposed 60 relatively at the angles shown, the rays of light are concentrated through opening 14 upon the picture and are equally diffused over its entire opaque surface and projected through the tube and lens to the screen. If 65 gas or oil lamps were used, the same relative arrangement of the lamps to the tube and to the picture would be retained, and the invention in its broadest aspect is to be construed to cover the use of any type or 70 form of lamp if constructed and arranged substantially as herein shown and described.

What I claim is:—

In projection lanterns, a body having a lens tube and lamp and a removable rear 75 wall having an opening opposite said lens tube, in combination with alternative picture display means jointly mounted upon said rear wall and removable therewith and comprising a swinging picture support at 80 one point and a rotatable picture support at another.

In testimony whereof I sign this specification in the presence of two witnesses.

CHARLES F. DUTTON, Jr.
